RECOIL CONTROLLING DEVICE APPLIED TO A RIFLE BARREL
WITH A BAYONET ATTACHED AND SUPPORTING MEANS FOR
THE BAYONET, THE DEVICE BEING ATTACHED TO THE Muzzle
OF THE BARREL AND THE BAYONET ATTACHED TO THE SUPPORT
MEANS.

STABILIZING DEVICE

Robert H. S. Hughes, Baltimore, Md., assignor of
one-half to Milton Roberts, Baltimore, Md.

Application September 6, 1935, Serial No. 39,492

4 Claims. (Cl. 89—14)

This invention relates to a device for minimizing recoil in fire arms which are adapted to fire projectiles. The invention comprises a body having means for its attachment to the muzzle of a gun barrel, said body having a gas chamber therein and having an inlet port and a seal port at the rear and forward sides of said chamber, respectively, and a shoulder extending laterally from the inner end of the seal port, the inner side wall of the chamber flaring outwardly and forwardly from the inlet port toward said shoulder, and discharge ports extending rearwardly and outwardly from the shoulder. When the device is mounted on the gun barrel the inlet port and the seal port are in line with the bore of the barrel. The chamber is relatively small and as the bullet leaves the gun barrel and passes into the seal port, the gases and still burning products of combustion from the barrel enter the chamber and create an exceedingly high pressure therein, particularly at the moment when the seal port is practically closed by the bullet. These gases are confined and directed against the shoulder at the forward end of the chamber by the forwardly and outwardly flaring side wall of the chamber and as the discharge ports lead rearwardly and outwardly from the shoulder, the force of the reaction from the discharge of the gases against the atmosphere is applied to the shoulder thus greatly reducing the recoil.

In the accompanying drawings, which illustrate the invention:

Fig. 1 is a side elevation of my recoil controlling device applied to a rifle barrel;

Fig. 2 is a longitudinal section on the line 2—2 of Fig. 1;

Fig. 3 is a transverse section through the recoil device on the line 3—3 of Fig. 2;

Fig. 4 is a longitudinal section through the recoil device mounted upon the end of a rifle barrel, the latter, with the sight thereon, being shown in side view, and a bullet being shown in the seal port of the device;

Fig. 5 is a graph showing the percentage of recoil eliminated in a regulation United States Army rifle shooting a standard cartridge for various total port areas given in square inches with a port angle of 30° to the longitudinal axis of the bore;

Fig. 6 is a side elevation of a modified form of recoil device applied to a rifle barrel and serving as a supporting means for a bayonet, the latter shown in side view partly broken away;

Fig. 7 is a longitudinal central section through the recoil device shown in Fig. 6, and,

Fig. 8 is a front end view of the same.

Referring to Figs. 1-5, inclusive, of the drawings, 1 indicates the barrel of a rifle with a wooden support 2 which is a continuation of the stock. At the end of the support 2 is shown a bayonet attaching member 3 provided with a pivoted link 4 through which the rest strap of the rifle (not shown) is adapted to pass. On the muzzle of the barrel 1 is mounted the front sight 5. The barrel is externally screw-threaded as shown at 6 and the bore of the barrel is rifled in the usual manner as indicated at 7.

The attachment for minimizing recoil comprises a cone-shaped metal body 8 formed with a cavity or gas chamber 9 therein and having a rearwardly extending sleeve or collar 10 with internal threads 10' adapted to engage the threads on the barrel. When the device is fitted onto a gun barrel, an annular shoulder 13^a at the inner end of the sleeve abuts against the end of the barrel, and the device is held against turning by a set screw 15. The inner boundary of this shoulder is concentric with the bore of the barrel and forms an inlet port 13^b to the chamber in the device. From the inlet port, the side wall 13 of the chamber flares forwardly and outwardly toward the periphery of an annular shoulder 14.

In the forward part of the device is a seal port 11 which is in line with said inlet port and with the bore of the gun barrel and the shoulder 14 extends laterally from the inner end of the seal port to the side wall of the chamber and forms the forward wall of the chamber. The side wall of the chamber closes the forward part of the chamber adjacent the shoulder 14 against the lateral escape of gases to the atmosphere. The device has a rearwardly facing external shoulder 8^a at the rear of the shoulder 14 in the chamber, and a plurality of straight discharge ports 12, arranged in a circular series, extend rearwardly and outwardly through the body from the forward part of the chamber adjacent the shoulder therein through said external shoulder, the axes of said discharge ports intersecting the shoulder in the forward part of the chamber, and the peripheries of said discharge ports, at their outer sides, being in line with the periphery of the internal shoulder 14.

In the operation of the device, when the gun is fired, the bullet passes through the inlet port and the chamber and thence through the seal port and the blast from the gun barrel, consisting of burned and still burning gases and products of combustion, is confined and directed forwardly against the shoulder 14 by the flaring side wall 13 of the

chamber. The shoulder 14 is so shaped that the gases are directed forwardly against the shoulder 14 and the peripheries of the discharge ports 12, at their outer sides, are in line with the periphery of the internal shoulder 14.

chamber. As the chamber or cavity is of relatively small size, the pressure created within the chamber is exceedingly high, especially during the moment when the seal port is substantially blocked by the bullet 16, as shown in Fig. 4, and hence the discharge of the gases through the discharge ports against the atmosphere is instantaneous and violent and the reaction force resulting from these discharges is applied directly to the forward shoulder 14 in the control device, thus greatly minimizing the recoil.

For each type of gun or piece of ordnance, the correct size of the chamber, size of gas shoulder and distance of the shoulder from the muzzle of the gun must be determined to gain the greatest efficiency. In general it is desirable to have the gas chamber relatively small since the smaller the chamber the greater the velocity of the gases leaving the discharge ports 12. It is also desirable to have the total area of the gas shoulder 14, as nearly as practicable, equal to the cross-sectional area of the rearwardly directed discharge ports.

With the type of recoil device shown in Figs. 1-4, as applied to a standard United States Army rifle, in which the rearwardly directed discharge ports were directed at an angle of approximately 30° to the longitudinal axis of the bore of the gun, I have found that the total area of the ports was a very important factor in eliminating recoil. The principles thus established apply also to other firearms.

Turning to the graph, which is based on the performance of a regulation United States Army rifle using a regulation cartridge, it will be seen that with a total area of .22 inch, 51% of the recoil is eliminated; with a total port area of .3, 61% is eliminated; with an area of .6 inch, 69% is eliminated. At this point the curve seems to flatten out and with the total port area of .77 inch, 72% of the recoil was eliminated, while with a total area of 1.2 inches, 74% was eliminated. From the curve constructed on the data obtained, it was obvious that the port area was a critical factor in determining the efficiency of the device, and that approaching a certain maximum port area, the curve of percentage of recoil elimination flattens out.

In Figs. 6, 7 and 8 of the drawings, I have shown a tubular extension 20 on the forward end of the conical body 8 through which the seal port 28 extends. This extension may be used, as shown in Fig. 6, to form a support for a bayonet 23, by passing the extension through a ring 21 on the guard 22 of the bayonet. The bayonet handle 24 is attached to the member 3 on the gun barrel by locking means indicated at 25, but not shown in detail.

What I claim is:

1. A recoil controlling device for guns adapted to fire projectiles comprising a body adapted for attachment to the muzzle end of a gun barrel, said body having a gas chamber therein and having an inlet port and a seal port at the rear and forward ends of said chamber, respectively, and a shoulder extending laterally from the inner end of the seal port to the side wall of the chamber, the side wall closing the forward part of the chamber adjacent said shoulder against lateral escape of gas, the side wall flaring outwardly and forwardly from the inlet port toward the periphery of said shoulder, said device having a rearwardly facing external shoulder at the rear of

the shoulder in the chamber, and having a plurality of discharge ports extending rearwardly and outwardly from the forward part of the chamber adjacent the shoulder therein through said external shoulder, the axes of said ports intersecting the shoulder in the forward part of the chamber.

2. A recoil controlling device for guns adapted to fire projectiles comprising a body adapted for attachment to the muzzle end of a gun barrel, said body having a gas chamber therein and having an inlet port and a seal port at the rear and forward ends of said chamber, respectively, and a shoulder extending laterally from the inner end of the seal port to the side wall of the chamber, the side wall closing the forward part of the chamber adjacent said shoulder against lateral escape of gas, the side wall flaring outwardly and forwardly from the inlet port toward the periphery of said shoulder, said device having a rearwardly facing external shoulder at the rear of the shoulder in the chamber, and having a circular series of straight discharge ports extending rearwardly and outwardly from the forward part of the chamber adjacent the shoulder therein through said external shoulder, the axes of said ports intersecting the shoulder in the forward part of the chamber.

3. A recoil controlling device for guns adapted to fire projectiles comprising a body adapted for attachment to the muzzle end of a gun barrel, said body having a gas chamber therein and having an inlet port and a seal port at the rear and forward ends of said chamber, respectively, and a shoulder extending laterally from the inner end of the seal port to the side wall of the chamber, the side wall closing the forward part of the chamber adjacent said shoulder against lateral escape of gas, the side wall flaring outwardly and forwardly from the inlet port toward the periphery of said shoulder, said device having a rearwardly facing external shoulder at the rear of the shoulder in the chamber, and having a plurality of discharge ports extending rearwardly and outwardly from the forward part of the chamber adjacent the shoulder therein through said external shoulder, the axes of said ports intersecting the shoulder in the forward part of the chamber, and the peripheries of the discharge ports, at their outer sides being in line with the periphery of the latter shoulder.

4. A recoil controlling device for guns adapted to fire projectiles comprising a conical body adapted for attachment to the muzzle end of a gun barrel and having a cylindrical extension at its forward end, said body having a gas chamber therein and having an inlet port and a seal port at the rear and forward ends of said chamber, respectively, the seal port extending through said cylindrical extension, and said body having a shoulder extending laterally from the inner end of the seal port to the side wall of the chamber, the side wall closing the forward part of the chamber adjacent said shoulder against lateral escape of gas, said device having a rearwardly facing external shoulder at the rear of the shoulder in the chamber and having a plurality of discharge ports extending rearwardly and outwardly from the forward part of the chamber adjacent the shoulder therein through said external shoulder, the axes of said ports intersecting the shoulder in the forward part of the chamber.

ROBERT H. S. HUGHES.
